Application October 7, 1934, Serial No. 83,844

15 Claims. (CL 177—337)

This invention relates, generally, to data transmission systems and the invention has reference, more particularly, to a novel two wire data transmission and control system employing A. C. voltages of fixed selected frequencies and constant magnitude, but of variable phase position.

Data transmission systems, i. e., electrical systems employed for transmitting various data such as angular data or data that are susceptible of indication on a suitable sheet, card or other member having relative movement with respect to a pointer or other designating means, as heretofore constructed, have generally required five or more wires extending between the transmitting or field station and the receiving or central station for transmitting a single channel of data. The use of a relatively large number of wires not only greatly increases the installation and maintenance expenses, but oftentimes the desired number of wires are not available for use in transmitting data, as during army maneuvers, where it is not practicable to string five or more wires from a transmitting station, such as an outpost, to a receiving or central station which may be several miles away.

In our copending application Serial No. 83,844 there is disclosed a novel data transmission and control system that employs but two wires extending between the remotely located transmitting and receiving points, the said system employing means for producing a synchronizing signal voltage of fixed frequency that is sent out from the receiver to the transmitter, at which station means is provided for converting such signal voltage to one of different frequency and variable phase position corresponding to the data transmitted, such different frequency voltage being sent back to the receiver, which latter is arranged to select the returning signal voltage and detect its phase position for use either in operating a follow-up indicator or, through use of a torque amplifier, to control a servo motor to effect the positional control of a heavy object.

The principal object of the present invention is to also provide a two-wire data transmission and control system using a variable phase, constant frequency signal voltage for transmitting the desired data, the present system, however, employing means at the transmitter for producing the data transmitting fixed frequency voltage of variable phase position and a synchronizing or timing voltage of different frequency and fixed phase position, both of which voltages are

sent over two wires, such as a commercial telephone line, to the receiver, which latter is provided with means for separating said voltages and detecting the phase shift of the data transmitting voltage for use either in operating a follow-up indicator or, through the use of a torque amplifier, to control a servo motor to effect the positional control of an object.

Another object of the present invention lies in the provision of a novel data transmission and control system of the above character that is entirely self-synchronous and continuously rotatable, the said system requiring but one data transmitting frequency voltage for each channel 15 of data transmitted, and being adapted to provide additional channels, if desired, over the same pair of wires by employing corresponding additional data transmitting frequencies at the transmitter, these additional frequencies being 20 separated from one another and from the synchronizing frequency by use of suitable filter means at the receiver.

Still another object of the present invention is to provide a novel data transmission and control system of the above character that is easy to operate and is reliable in use, the said system employing a small and compact transmitter that can be readily carried from place to place.

Other objects and advantages will become apparent from the specification, taken in connection with the accompanying drawings wherein one embodiment of the invention is illustrated.

In the drawings.

Fig. 1 is a schematic view showing a two-channel, two-wire data transmission system of this invention arranged for automatic follow-up.

Figs. 2a and 2b are a wiring diagram of the system of Fig. 1, and Fig. 3 shows the system adapted for radio transmission.

Similar characters of reference are employed in the above views to indicate corresponding parts.

Referring now to Fig. 1 of the drawings in connection with a brief description of a two-channel system arranged for automatic follow-up, the reference numeral 1 designates a storage battery connected to supply motor operating current to a motor-generator set 2 that has generator windings adapted to supply a single phase output of one frequency through leads 3 and two three-phase outputs of different frequencies through cables 4 and 5.

If more than two channels of data transmission are desired, the generator portion of motor-generator set 2 is provided with additional wind-

ings for producing additional three-phase outputs, each of which is of a different frequency from the others. Thus, additional cables 4' and 5' are shown extending from motor-generator set 2, indicating that this set is capable of providing transmission frequencies for four channels of data, if desired.

Leads 3 extend to the single phase rotor windings of transmitter inductive devices 6 and 6' having three-phase stator windings connected respectively to cables 4 and 5. Leads 3 are also shown broken off to indicate that the same are adapted to extend to the single phase windings of additional transmitter inductive devices (not shown) similar to 6 and 6', having three-phase stator windings connected respectively to the cables 4' and 5', should two additional channels of data transmission be desired, thereby providing four channels of data transmission over two wires. Four channels of transmission are particularly convenient in the operation of anti-aircraft and seacoast defense fire control equipment since the same permit one to one and multiple speed transmission in both train or azimuth and elevation.

From inductive devices 6 and 6' of the transmitter the leads 3 extend to the two-wire transmission line 3', which may be a commercial telephone line. Thus, the single phase current of, for example, 100 cycle frequency constituting the synchronizing or timing signal and supplied by leads 3, passes through the rotor windings of devices 6 and 6' in series to the line 3' and over this line, which may be several miles long to the receiver or receiving station.

At the receiver there is provided a line amplifier 7 that restores the received signal voltage to a suitable value, which signal is then passed to a band pass filter 8. If the rotor of either of the inductive devices 6 or 6' is angularly shifted or turned by suitable means, such as shown in our above mentioned copending application, causing a similar turning of indicator discs 10 or 10' attached to the rotors thereof, then a single phase voltage of changing phase position is applied to leads 3 at the rotor terminals of the shifted device, which voltage has a frequency depending upon the frequency of the three-phase supply to the stator winding of such device. If the frequency of the three-phase supply through cable 4 to the stator of inductive device or Selsyn 6 is 150 cycles, then the single phase voltage applied by this device to leads 3 will also be of 150 cycles frequency. The phase position of the voltage thus applied to leads 3 will be shifted one degree for each degree the rotor of the device is turned.

Thus, there is supplied to line 3' (in the absence of additional inductive devices connected to cables 4' and 5') three frequencies, a timing frequency of, for example, 100 cycles, and two signalling frequencies of, for example, 150 and 250 cycles, the phase positions of which latter frequencies may be shifted at will by turning the rotors of devices 6 and 6'. At the receiver or receiving station a band pass filter 8 separates these three frequencies, passing the timing frequency through leads 19 to an amplifier 11 that builds up this frequency to a voltage value sufficient for operating the synchronous driving motor of a motor-generator set 12, thereby causing this set to run synchronously with the motor-generator set 2 at the transmitter. The band pass filter 8 passes the 150 cycle signal voltage received from inductive device 6 through leads

18 to a box 15 containing detecting and amplifying apparatus. Likewise the filter 8 passes the 250 cycle signal voltage received from inductive device 6' through leads 17 to another box 22 containing detecting and amplifying apparatus.

At the receiving station there is provided receiving inductive devices 13 and 13' similar to devices 6 and 6'. The three-phase stator of device 13 is supplied from motor-generator set 12 through cable 14 with three-phase current of the same frequency that is supplied to the stator of device 6, for example, 150 cycles, whereas device 13' is similarly supplied through cable 16 with three-phase current of the same frequency as that supplied to the stator of device 6'. The rotors of devices 13 and 13' are respectively connected through leads 18 and 20 to the detector-amplifiers 15 and 22, which latter are connected through cables 25 and 26 to motors 23 and 23' that are connected through suitable gearing 29 for turning the respective rotors of devices 13 and 13'.

Any turning of the rotor of transmitter device 6 shifts the phase of its output signalling voltage with respect to the timing voltage and the phase shift is supplied through leads 18 and appears at the device 15 of the receiver, within which this voltage is compared with the phase of that supplied through leads 19 from the receiver inductive device 13. Any departure from predetermined fixed relative phase positions of these voltages corresponding to the synchronous positioning of transmitter indicator disc 10 with receiver indicator disc 27, resulting from the turning of the transmitter rotor, will cause detector-amplifier 15 to operate motor 23 so that the latter, acting through gearing 29, serves to turn the rotor of inductive device 13 to restore its output to phase alignment with the incoming signal, thereby causing indicator 27 to follow the movements of indicator 10.

The second channel of transmission acts in like manner so that as transmitter inductive device indicator disc 10' is turned, the motor 23' is caused by detector-amplifier 22 to turn indicator disc 27' by a like amount. Cables 14' and 16' are shown extending from motor-generator 12 for supplying three phase current to two additional receiver inductive devices in the event that four channels of transmission are desired, the respective signalling voltages of differing frequencies for the detector-amplifiers (not shown) of said additional receiver inductive devices being supplied from filter 8 through leads 30 and 31.

Referring now to Figs. 2a and 2b, showing the wiring diagram of the system of Fig. 1 in detail, the motor 28 of the motor-generator set 2 is shown provided with a centrifugal speed control device 33 and has a single phase, inductive type generator rotor 34 on its drive shaft and a plurality of three-phase generator rotors 35, 36, 37 and 38. Rotor 34 is associated with single-phase generator winding 39 for the generation in the latter of the low frequency synchronizing or timing signal which in the example previously given was assumed as 100 cycles. Rotors 35 and 36 are associated with three-phase generator windings 40 and 41 for the generation in the latter of three-phase voltages of different frequencies, assumed as 150 and 250 cycles in the example previously given, which voltages are respectively communicated to the stator windings 42 and 43 of the inductive devices 6 and 6'. The single-phase rotor windings 44 and 45 of these inductive devices are connected in series with

each other through the slip rings shown to the winding 38, and through the telephone or other two-wire line 3' to the receiving station.

A transformer 46 at the receiver couples the line 3' to an attenuator 47 which, in turn, is coupled by transformer 48 to the push-pull amplifier 7 that serves to amplify the synchronizing and signal voltages which are delivered through output transformer 49 to the band pass filter 8. A voltmeter or volume indicator 50 is shown connected across the output of transformer 49. By adjusting the attenuator 47 to get a desired reading of meter 50, variations in the length and hence attenuation of line 3' may be compensated for.

Section 51 of the band pass filter 8 selects the timing frequency and supplies the same through leads 9 and thermionic amplifier 11 to the synchronous motor 52 of the motor generator set 12. Motor 52 is illustrated as a single-phase machine provided with a D. C. excitation winding on the rotor. In practical use, a starting winding is provided on motor 52 to make it self-synchronizing. Motor 52 has a plurality of three-phase inductive type generator rotors on its drive shaft two of which, designated 53 and 54, are shown in the drawings, which rotors cooperate with three-phase windings 55 and 56 for the generation in the latter of three-phase voltages of frequencies corresponding respectively to those produced by windings 40 and 41 of motor-generator 2.

Section 57 of the band pass filter 8 selects the signalling frequency put into the line 3' by inductive device 6 and supplies the same through leads 18 to an input transformer 58 of the phase detector-amplifier 15. Transformer 58 passes this signal in 180° out of phase relation to the plates of diode phase detector rectifier tubes 59 and 59'. The plates of diode tubes 59 and 59' are also supplied with the single phase voltage output of the receiver inductive device 13 by means of leads 19 and transformer 68. When the voltages across transformers 58 and 68 are 90° out of phase with each other, their vector sums applied to the plates of tubes 59 and 59' are equal, and the rectified voltage drops obtaining across resistors 61, 61' in the external cathode-plate circuits of these tubes are equal and opposite. A low pass filter 63 is connected across resistors 61 and 61' so that with the voltage drops across these resistors equal and opposite, there is no net voltage drop across points 62 and 62' at the output of this filter. However, when the rotor of the transmitter inductive device 6 is turned with respect to the rotor of inductive device 13, causing the phase of its output signalling voltage to shift relative that of device 13, the voltage across transformer 58 will shift from its 90° relation with that across transformer 68, causing the voltages across resistors 61 and 61' to become unequal, since one of the tubes 59 or 59' will pass more current than the other depending upon the direction in which the device 6 is turned, and a D. C. signal voltage drop will appear across points 62, 62'. This voltage is divided through resistors 64 and 64' and is communicated to the control grids of modulator tubes 66 and 66' arranged in push-pull. An A. C. bias voltage is also supplied from a transformer 68 through resistors 64, 64' to the control grids of tubes 66, 66'. The plates of tubes 66 and 66' are supplied with a D. C. voltage through the divided primary of output transformer 61. Tubes 66 and 66' are provided with a degenerating network

consisting of resistance 65 and condenser 66 to prevent oscillation, and 70 designates a fixed bias resistor.

With a D. C. signal voltage applied to tubes 66, 66' together with an A. C. bias voltage from transformer 68, there appears in the plate circuits of these tubes A. C. voltages passing through the halves of transformer 67. When the currents drawn by tubes 66, 66' are unequal, a net A. C. voltage passes through transformer 61 and to the grids of amplifier tubes 70, 70' that are arranged in push-pull and are connected to the output terminals of transformer 61. The plates of tubes 70 and 70' are supplied with A. C. voltage from a transformer 81 connected to commercial frequency supply leads 88 that also supply transformer 68. A phase correcting network 88' is included in the connection between transformer 81 and tubes 70 and 70'. The net A. C. signal voltage applied to tubes 70 and 70' causes these tubes to draw unequal plate currents through the halves of an inductance 71 and resistors 72, 72'. Since the plate supply to these tubes is A. C., the drop across the plate circuit impedance contains both an A. C. and a D. C. voltage component. The A. C. component is improved in wave form by condenser 74 and passes through condensers 75, 75' to the grids of grid controlled, gaseous rectifier tubes 76, 76'. A phase bias voltage is applied to the grids of tubes 76, 76' from secondary winding 79 of transformer 81 through the use of phase shift condenser and resistor, 81, 88. The A. C. voltage component appearing across resistors 82, 82' thus adds vectorially with the bias A. C. voltage so as to advance the phase of the voltage appearing at one of the rectifier grids while simultaneously retarding the phase of the voltage at the other. The plate currents drawn by these tubes from supply 88 through the differentially wound motor 23 are thereby unbalanced, causing this motor to operate through gearing transmission 29 to turn the rotor 85 of receiver inductive device 13 in the proper direction to move receiver indicator disc 27 into synchronism with transmitter indicator disc 16, the turning of rotor 85 serving to again position the voltages across transformers 58 and 68 at right angles to one another. If desired, a ponderable object such as a searchlight 83, driven from motor 23, may thusly be controlled from the transmitter by turning the rotor of inductive device 6.

The operation of the second channel of transmission is similar to that just described in connection with the first channel, the signalling voltage supplied from transmitter inductive device 6' through line 3' passing through section 188 of filter 8 and feeding into detector-amplifier 22, which detector-amplifier may be used to control motor 23' for automatically positioning the receiver indicator disc 27', as shown in Fig. 1 or as shown in Fig. 2b, where manual operation of the receiver indicator disc is desired, the output voltage of diode phase detecting rectifiers 59, 59', taken across resistors 61, 61', is shown employed to operate a zero center or right and left indicating meter 89. The operator at the receiver observes meter 89 and turns the rotor 90 of receiver inductive device 13' so as to cause the meter 89 to read zero, thereby positioning the indicator disc 27' (see Fig. 1) in angular alignment with the indicator disc 16' at the transmitter.

If desired, the two wire transmission line 3' may be dispensed with and a radio transmitter installed at the transmitting station and a radio

receiver installed at the receiving station. Such an arrangement is shown in Fig. 3, wherein an amplifier 84 is shown connected to leads 3 at the transmitter, which amplifier feeds the amplified timing and signalling voltages to a modulator 85 that is supplied with a radio frequency carrier voltage from the oscillator 86. Modulator 85 feeds the transmitter antenna 81 and the signals received by receiver antenna 82 are fed to demodulator 83, the audio output of which is supplied to amplifier 7 of the receiving station, which in turn supplies the same to filter 8, as before.

It will be apparent that, if desired, a power transmission line may be used for conveying the signal potentials, preferably at a frequency higher than the frequency of the power current of the line, from the transmitting to the receiving station, and in such case the transmission of a timing potential is not essential since synchronous motor-generator sets supplied from the line may be used at the transmitter and receiver for supplying three phase currents to the inductive devices.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. In some instances a single wire and ground may be used in lieu of two wires, although the operation would not ordinarily be so good, so that the expression "two wire transmission line" in the claims is intended to cover such a possible structure.

What is claimed is:

1. In a control system of the character described, a two-wire transmission line, a transmitting station connected to said line, a receiving station connected to said line remote from said transmitting station, controlling means at said transmitting station including an A. C. generator and an inductive device energized therefrom for delivering electric signal impulses of changing phase to said line in accordance with desired data for transmission to said receiving station, means at the latter station for detecting the phase of said signal impulses and including an A. C. generator operating synchronously with said transmitting station generator, and controlled means including an inductive device at said receiving station energized from said receiving station generator and operable from said detecting means in synchronism with said controlling means.

2. In a data and control system, a transmitting station, an A. C. voltage supply, a two-wire transmission line supplied with a single phase timing voltage from said supply, a transmitter inductive device supplied with polyphase voltage from said supply and operable to deliver a single phase signal voltage continuously variable as to phase position, the single phase signal voltage output of said inductive device being supplied to said line, and a receiving station connected to said line at a remote point, a receiver inductive device, filtering means for selecting said single phase timing voltage for use in supplying said receiver inductive device with polyphase current that is synchronous with that supplied to said transmitter inductive device, a detector-amplifier connected for receiving the single phase signal voltage output of said receiver inductive device, said filtering means selecting said single phase signal volt-

age output of said transmitter inductive device for application to said detector-amplifier for comparison and combination with said receiver inductive device signal voltage output, and means controlled from the output of said detector-amplifier for use in synchronizing said transmitter and receiver inductive devices.

3. In a data transmission and control system, an A. C. voltage supply, a radio transmitter having its carrier modulated with a single phase timing voltage from said supply, a transmitter inductive device supplied with polyphase voltage from said supply and operable to deliver a single phase signal voltage variable as to phase position, the single phase signal voltage output of said inductive device being also supplied so as to modulate said radio transmitter carrier with a variable phase signal, a remote radio receiver, a receiver inductive device, filtering means supplied from said radio receiver, said filtering means selecting said received and detected single phase timing voltage for use in supplying said receiver inductive device with polyphase current that is synchronous with that supplied to said transmitter inductive device, a detector-amplifier connected for receiving the single phase signal voltage output of said receiver inductive device, said filtering means selecting said received and detected single phase signal voltage output of said transmitter inductive device for application to said detector-amplifier for combination with said receiver inductive device signal voltage output, and means controlled from the output of said detector-amplifier for use in synchronizing said transmitter and receiver inductive devices.

4. In a data transmission and control system, a transmitting station comprising a constant speed generator, a transmitter inductive device supplied with polyphase voltage from said generator and operable to deliver a single phase signal voltage variable as to phase position, a two-wire transmission line supplied with single phase timing voltage from said generator, the single phase signal voltage output of said transmitter inductive device being supplied to said line, and a receiving station connected to said line at a remote point, said receiving station comprising a synchronous motor-generator set, filtering means for selecting said transmitter generator single phase timing voltage for use in operating the synchronous motor of said set, whereby a polyphase voltage output of the generator of said set is synchronous with that supplied to said transmitter inductive device, a receiver inductive device supplied with said polyphase voltage output of said set, a detector-amplifier for receiving the single phase signal voltage output of said receiver inductive device, said filtering means selecting said single phase signal voltage output of said transmitter inductive device for application to said detector-amplifier for comparison and combination with said receiver inductive device signal voltage output, the output of said detector-amplifier serving for use in synchronizing said transmitter and receiver inductive devices.

5. In a data transmission and control system, a transmitting station comprising a constant speed generator, a transmitter inductive device supplied with polyphase voltage from said generator and operable to deliver a single phase signal voltage continuously variable as to phase position, a two-wire transmission line supplied with single phase timing voltage from said generator, the single phase signal voltage output of said transmitter inductive device being supplied

to said line, and a receiving station connected to said line at a remote point, said receiving station comprising a synchronous motor-generator set, filtering means for selecting said transmitter generator single phase timing voltage for use in operating the synchronous motor of said set, whereby a polyphase voltage output of the generator of said set is synchronous with that supplied to said transmitter inductive device, a receiver inductive device supplied with said polyphase voltage output of said set, a detector-amplifier for receiving the single phase signal voltage output of said receiver inductive device, said filtering means selecting said single phase signal voltage output of said transmitter inductive device for application to said detector-amplifier for comparison and combination with said receiver inductive device signal voltage output, and motive means operated from said detector-amplifier for maintaining said receiver inductive device in synchronism with said transmitter inductive device.

6. In a data transmission and control system, a transmitting station having means for supplying an A. C. timing voltage, a movable control member, and means responsive to movement of said control member for supplying a variable phase signal voltage, a remote receiving station, means for transmitting said timing and signal voltages to said receiving station, said latter station having thermionic control means, a movable controlled member operated therefrom, and means energized in response to said timing voltage and responsive to movement of said controlled member for supplying a variable phase receiver voltage, and means for causing said receiver voltage to act jointly with said signal voltage to determine the operation of said thermionic control means, and hence of said controlled member.

7. A data transmission and control means as defined in claim 6, wherein said thermionic control means comprises push-pull phase detector-rectifiers having their plates supplied not only with said variable phase receiver voltage in in-phase relation, but also supplied with said variable phase signal voltage in 180° out of phase relation, the vector addition of said voltages serving to determine the action of said detector-rectifiers, and hence of said controlled member.

8. A data transmission and control means as defined in claim 6, wherein said thermionic control means comprises push-pull phase detector-rectifiers having their plates supplied not only with said variable phase receiver voltage in in-phase relation but also supplied with said variable phase signal voltage in 180° out of phase relation, the vector addition of said voltages serving to determine the action of said detector-rectifiers, modulator means for receiving and modulating the D. C. voltage output of said detector-rectifiers, an amplifier for amplifying the output of said modulator means, and a motor controlled from the output of said amplifier, said motor being connected in driving relation to said controlled member for moving the latter in synchronism with said control member.

9. In a data transmission and control system, a controlling object, a controlled object, and synchronizing means for moving said controlled object in response to movements of said controlling object, said synchronizing means comprising means near said controlling object for supplying a timing voltage and a signal voltage variable in phase with movement of said controlling object,

means for transmitting said voltages, and means near said controlled object and connected therewith for receiving said transmitted voltages and for determining the movement of said controlled object in accordance therewith.

10. In a data transmission and control system for multiple channel transmission, a transmitting station having means for producing a synchronizing A. C. single phase voltage and a plurality of polyphase voltages of different frequencies, a plurality of transmitters for receiving said polyphase voltages and for delivering variable phase signal potentials of corresponding frequencies, transmission means comprising but two wires for transmitting said single phase voltage and said signal potentials, a remote receiving station for receiving said voltage and potentials, said receiving station having a plurality of receivers, generating means controlled from said synchronizing A. C. voltage for supplying polyphase voltages to said receivers corresponding to those supplied to said transmitters, and data indicators controlled in response to said signal potentials and to potentials supplied from said receivers.

11. In a data transmission and control system, a transmitting station having means for supplying an A. C. timing voltage, a movable control member, and means responsive to movement of said control member for supplying a variable phase signal voltage, a remote receiving station, a controlled member at said receiving station, means for transmitting said timing and signal voltages to said receiving station, said latter station having push-pull phase detector-rectifier means, meter means operated therefrom, and means energized in response to said timing voltage and responsive to movement of said controlled member for supplying a variable phase receiver voltage for acting jointly with said signal voltage to determine the operation of said detector-rectifier means, and hence of said meter means.

12. A data transmission and control system comprising a transmitter and a remotely located receiver, said system comprising a two-wire transmission line as the only conducting means interconnecting said transmitter and receiver, said transmitter having means for delivering a fixed phase timing voltage and a variable phase signal potential that is variable without limit and corresponding to the data transmitted to said line for transmission to said receiver, and said receiver having means for selecting and detecting the phase position of said signal potential with respect to a version of said timing voltage for use in visually indicating the data transmitted.

13. In a control system of the character described, a two-wire transmission line, transmitting means for delivering a fixed phase timing voltage to said transmission line, said transmitting means including a variable phase transmitter having a controlling member and arranged for delivering electric signal impulses of changing phase to said line, said signal impulses being variable without limit as to phase in accordance with the position of said controlling member, receiving means for receiving said fixed phase timing voltage and comprising a variable phase receiver connected to said line for receiving said changing phase signal impulses, and a controlled member located at said receiver, said receiver having means for detecting the phase position of said signal impulses with respect to a fixed phase voltage derived from said timing voltage and for

operating said controlled member in response thereto, whereby said controlled member is moved synchronously with said controlling member, said two-wire transmission line constituting the only electrical connection between said transmitter and receiver.

14. A signalling system comprising in combination a transmission line consisting of but two conducting paths extending between a transmitting point and a receiving point, means including generating means and the line for providing at both points, fundamental electric waves of substantially the same constant frequency and phase position, means at the transmitting point utilizing output from said generating means for delivering to the line, waves of the fundamental frequency but in any phase displacement within 360 degrees relative to the phase of the fundamental waves, the displacements being proportional to indications to be transmitted, and means at the receiving point for detecting and indicating the amount of the phase displacement.

15. A signalling system comprising in combination a transmission line consisting of but two conducting paths extending between a transmitting point and a receiving point, means including generating means and the line, for providing at both points fundamental electric waves of substantially the same constant frequency and phase position, angularly movable means at the transmitting point, utilizing output from said generating means for delivering to the line, waves of the fundamental frequency but in any phase displacement within 360 degrees relative to the phase of the fundamental waves, and proportional to the angular movement of the said angularly movable means, the angular movement being the signal data to be transmitted and means at the receiving point for detecting the phase displacements and for translating the displacements into proportional angular movements.
